UNITED STATES PATENT OFFICE.

SAMUEL R. SHOUP, OF HOBOKEN, NEW JERSEY.

AUTOGRAPHIC REGISTER.

1,098,335.

Specification of Letters Patent.

Patented May 26, 1914.

Application filed November 18, 1909, Serial No. 527,776. Renewed October 16, 1913. Serial No. 795,563.

To all whom it may concern:

Be it known that I, SAMUEL R. SHOUP, a citizen of the United States, and a resident of Hoboken, in the county of Hudson and State of New Jersey, have invented certain new and useful Improvements in Auto-graphic Registers, of which the following is a specification.

This invention relates to what are generally known as autographic registers, such devices comprising a suitable casing within which are mounted a plurality of rolls of paper strips, each usually having a series of printed forms thereon, which strips are adapted to be brought over a suitable tablet or platen with manifolding material therebetween, whereby words or characters which are written upon the top strip will be automatically transferred to the strips underneath, after which the portions of the strips which have been written upon are withdrawn from the casing and detached, thereby drawing new portions or forms upon the tablet or platen for another writing operation. It is well known to those familiar with the use of these devices, that the principal difficulties encountered are, first, that of keeping the printed forms of the various strips in proper register with each other; second, that of insuring withdrawal of the superposed ends of the strips through precisely the proper distance, so that the forms detached may be of the right size and the forms left on the tablet or platen in proper position for the next succeeding writing operation. Particularly, where mechanical means are employed to advance the paper strips, automatically checking movement thereof at the proper point with or without the provision of means for severing the projecting end portions of the strips, it is important that such mechanism operate with the utmost precision, slight and immaterial variations during the first of a series of operations gradually increasing until during the last of such series the forms are completely out of register both with the tablet or platen and with each other. Furthermore, it is sometimes desired to provide for the retention within the casing of one of the strips for purposes of record, in such manner that it will be inaccessible ex-

cept to an authorized party or parties, this being sometimes done by re-rolling said strip upon another spool within the casing, although this is subject to the objection that the entire strip must be unwound to render some one form accessible for inspection. It is also true that when mechanical means are employed for detaching the end portions of the strips, the record strip also must be severed, and stored within the casing in some manner other than that of re-rolling.

The principal object of the present invention is the provision of a device of this character which will insure the withdrawal of just the proper lengths of strips after each writing operation, which will keep the printed forms in perfect register, and which will automatically sever the end portions of the strips which have been written upon and withdrawn, delivering one or more thereof to accessible position and storing another thereof in convenient form within the locked casing.

My invention will be more readily understood by reference to the accompanying drawings, forming a part of this specification, in which—

Figure 1 is a longitudinal vertical section of an autographic register embodying my invention; Fig. 2 is a transverse section thereof, taken substantially on the line 2—2 of Fig. 1, and Fig. 3 is a vertical section taken substantially on the line 3—3 of Fig. 2.

Referring now to the drawings in detail, numeral 11 refers to a suitable metallic casing of common and well-known form and construction, mounted upon the usual base-board 12. In the side walls of the casing are mounted in the usual manner the spools upon which are wound the usual rolls 13 of paper strips, generally three in number. From these rolls, the paper strips are passed over suitable idler rollers 14 and 15 across a tablet or platen 16 below a corresponding orifice 17 in the top face of the casing, where carbon sheets, or other suitable manifolding material, are interposed between the strips in such manner as to be held stationary while said strips are drawn across the same. At the forward end of the platen 16, are journaled the grip rollers 17 and 18, preferably yieldingly held in close

contact with each other to frictionally engage the superposed strips which are advanced in the usual manner upon rotation of said rollers. At the end of said rollers are 5 provided the meshed gears 19 and 20, respectively, insuring equal velocities when said rollers are rotated. Preferably the lower roller 17 is provided with a crank 21, exterior of the casing, by means of which 10 these rollers are rotated. Journalized in the side walls of the casing is the shaft 22, driven by means of a gear 23 from the roller 17 through the interposed gears 24 and 25 in mesh with each other and with the gears 19 15 and 23, respectively.

Mounted upon the base of the casing are the standards 26 26, in which is journaled the shaft 27, loose upon which is the drum 28 to which is secured the gear 29. Within 20 the drum 28 is provided a spiral spring 30 having one end thereof secured to the outer wall of the drum and the inner end thereof to the shaft 27. On the shaft 22 is provided a pinion 31 in mesh with the gear 29 and 25 adapted, upon rotation of the roller 17 in the direction to advance the strips, to rotate said drum against the action of the spring 30 and thus store energy in said spring to rotate the shaft 27. Mounted on said shaft 30 27, one on each side of the drum 28 are the spiral cam disks 32 and 32', each provided with a step adapted to be engaged by the detents 33 and 34, respectively. These detents are each spring-pressed, as shown, in 35 the direction of said stop-disks, and each is provided with a tapering or wedge-shaped extremity adapted to be engaged by a pin projecting from the drum 28, the pin 35 being adapted to engage the detent 33 and 40 withdraw the same from the stop in the disk 31, and the pin 36 being adapted to engage the inclined face of the detent 34 and withdraw the same from the stop in the cam disk 31'.

45 Mounted in suitable slide bearings in the side members of the frame 37, is the knife 38, adapted to reciprocate vertically, and upon reciprocation between the cross-bars 39 and 40 of the casing, to sever the tapering strip at this point. The shaft 27 is provided with the cranks 41 and 42 at the ends thereof, while connecting rods 43 and 44, respectively, are pivoted to the ends of 50 said cranks and to the ends of the arms or brackets 45 and 46 secured to the knife 38.

55 Mounted in the side members of the casing 11 is the cross bar 47, which is preferably tapering in order to direct the two upper strips of paper to accessible position 60 exterior of the casing, the lower strip passing beneath the same, as shown in Fig. This bar 47 is provided with apertures 48 through which pass the "spike-files" or stabbers 49 which are mounted upon the

knife 38. These "spike-files" or stabbers 65 49 preferably comprise a horizontal portion, the end of which is secured to the knife and projects forwardly therefrom, being bent to provide the vertical portion, as shown, at the upper end of which is provided the head 70 50 which tapers to a piercing point adapted to penetrate and pass through the lower sheet and engage the same in the usual manner to carry it downwardly upon downward movement of said knife and stabbers. 75

Below the bar 39 and in front of the rollers 17 and 18, I prefer to provide the comparatively thin guide bars 51 and 52, designed to separate the lower from the two upper strips of paper, the lower strip passing 80 between the guides 51 and 52 and the other strips passing between the guide 47 and the bar 39. These members are so positioned as to hold the paper strips in proper position for the operation of the knife 38. It will 85 now be apparent that when the crank 21 is rotated in the proper direction, the gripping rollers 17 and 18 will advance the paper strips across the platen 15, the two upper strips passing out of the casing in the manner shown and the lower strip being guided by the member 47 into the forward end of the casing. As the roller 17 is rotated, the gear train will effect rotation of the shaft 22 and through the pinion 31 rotate the 90 gear 29 and store energy in the spring 30. As said gear 29 and the drum 28 are rotated, the pins 35 and 36 will advance, one slightly ahead of the other for reasons which will be hereinafter explained, operating in turn 95 to withdraw the detents 34 and 33, on each occasion releasing the shaft 27 for rotation first through a slight arc which is checked by the detent 33 and next through a much longer arc and again checked by the 100 detent 34. Rotation of the shaft 27 will, through the cranks 41 and 42, reciprocate the knife 38 and therewith the "spike-files" or stabbers 49. As the knife is raised, the 105 end portions of all three strips are detached, the stabbers 49 passing upwardly through the apertures 48, thus piercing the lowest detached sheet, and operating to return the same with said stabbers into the receptacle therefor in the forward part of the casing. 110 The two upper detached sheets are removed for use in the usual course of business.

The spring 30 should be of considerable power in order that the knife and stabbers may be reciprocated with great rapidity and 115 thoroughly perform their functions. If this spring is made sufficiently powerful, it will be apparent that if one detent alone be employed, there would be a possibility that the shaft 27, rotating with such great velocity, 120 would make one revolution prior to the detent being returned to position to stop the same. On this account, I provide two de-

tents, the first releasing said shaft for a short arc and then returning to operative position and insuring the engagement of the disk when said other detent has been withdrawn to 5 release the shaft for its rotation through the great arc. It will be furthermore apparent that the spring 30 is self-winding, being wound from the gripping rollers 17 and relieved upon each rotation of the shaft 27. 10 Obviously, a spring-pressed detent 50' must be provided to hold the drum 28, through the gear 29, against rotation under action of the spring 30.

Many modifications of minor details of 15 my improved autographic register will doubtless suggest themselves to those skilled in the art to which it appertains, and I therefore do not desire to limit my invention to the specific construction hereinafter 20 shown and described.

I claim as new and desire to secure by Letters Patent:

1. In an autographic register, the combination, with means for rotatably mounting 25 a plurality of rolls of paper strips with the end portions of said strips directed over a suitable platen, of a knife adapted to be reciprocated across the path of movement of said strips, normally checked means constantly tending to reciprocate said knife, and means for releasing said reciprocating means when a predetermined length of strip has been drawn across said platen.

2. In an autographic register, the combination, with means for rotatably mounting 35 a plurality of rolls of paper strip with the end portions of said strips directed over a suitable platen and means for advancing said strips across said platen, of a knife 40 adapted to be reciprocated across the path of movement of said strips, normally checked means constantly tending to reciprocate said knife, and means actuated by said strips-advancing means to release said 45 reciprocating means when a predetermined length of strip has been drawn across said platen.

3. In an autographic register, the combination, with means for rotatably mounting 50 a plurality of rolls of paper strips with the end portions thereof directed over a suitable platen, of a knife adapted to be reciprocated across the path of movement of all of said strips, a piercing file adapted to be reciprocated across the path of movement of one of said strips only and engage said strip, normally checked means constantly tending to reciprocate said knife and said file, and means for releasing said reciprocating means 55 when a predetermined length of strip has been drawn across said platen.

4. In an autographic register, the combination, with means for rotatably mounting 60 a plurality of rolls of paper strips with the

end portions thereof directed over a suitable 65 platen, of a knife adapted to be reciprocated across the path of movement of all of said strips, a piercing file adapted to be reciprocated across the path of movement of one of said strips only and engage said strip, normally checked means constantly tending to reciprocate said knife and said file, and means actuated by said strip-advancing means to release said reciprocating means when a predetermined length of strip has 75 been drawn across said platen.

5. In an autographic register, the combination, with means for rotatably mounting a plurality of rolls of paper strips with the end portions thereof directed over a suitable 80 platen, of a knife adapted to be reciprocated across the path of movement of said strips, a spring for reciprocating said knife, means for checking movement of said knife under action of said spring, and means for 85 releasing said checking means when a predetermined length of strip has been drawn across said platen.

6. In an autographic register, the combination, with means for rotatably mounting a plurality of rolls of paper strips with the end portions thereof directed over a suitable 90 platen, of a knife adapted to be reciprocated across the path of movement of said strips, a spring for reciprocating said knife, 95 means normally checking movement of said knife under action of said spring, and means for automatically releasing said checking means when a predetermined length of strip has been drawn across said platen. 100

7. In an autographic register, the combination, with means for rotatably mounting a plurality of rolls of paper strips with the end portions thereof directed over a suitable platen, of a knife adapted to be reciprocated 105 across the path of movement of said strips, a spring for reciprocating said knife, means normally checking movement of said knife under action of said spring, means for automatically releasing said checking means 110 when a predetermined length of strip has been drawn across said platen, and means for restoring the energy of said spring by the operation of withdrawing said strips. 115

8. In an autographic register, the combination, with means for rotatably mounting a plurality of rolls of paper strips with the end portions thereof directed over a suitable platen, and means operable to advance said strips in unison across said platen, of a knife 120 adapted to be reciprocated across the path of movement of said strips, normally checked means constantly tending to reciprocate said knife, and means actuated by said advancing means to release said checking means when a predetermined length of strip has been drawn across said platen. 125

9. In an autographic register, the combi-

- nation, with means for rotatably mounting a plurality of rolls of paper strips with the end portions thereof directed over a suitable platen, and means operable to advance said strips in unison across said platen, of a knife adapted to be reciprocated across the path of movement of said strips, a spring for reciprocating said knife, means normally checking movement of said knife under action of said spring, and means actuated by said advancing means for automatically releasing said checking means when a predetermined length of strip has been drawn across said platen.
15. 10. In an autographic register, the combination, with means for rotatably mounting a plurality of rolls of paper strips with the end portions thereof directed over a suitable platen, and means operable to advance said strips in unison across said platen, of a knife adapted to be reciprocated across the path of movement of said strips, a spring for reciprocating said knife, means normally checking movement of said knife under action of said spring, means actuated by said advancing means for automatically releasing said checking means when a predetermined length of strip has been drawn across said platen, and means for restoring the energy of said spring by the operation of withdrawing said strips.
20. 11. In an autographic register, the combination, with means for rotatably mounting a plurality of rolls of paper strips with the end portions thereof directed over a suitable platen, of a knife adapted to be reciprocated across the path of movement of one of said strips only and engage said strip, a spring for reciprocating said knife and said file, means for checking movement of said knife and file under action of said spring, and means for releasing said checking means when a predetermined length of strip has been drawn across said platen.
25. 12. In an autographic register, the combination, with means for rotatably mounting a plurality of rolls of paper strips with the end portions thereof directed over a suitable platen, of a knife adapted to be reciprocated across the path of movement of one of said strips only and engage said strip, a spring for reciprocating said knife and said file, means normally checking movement of said knife and file under action of said spring, and means for automatically releasing said checking means when a predetermined length of strip has been drawn across said platen.
30. 13. In an autographic register, the combination, with means for rotatably mounting a plurality of rolls of paper strips with the end portions thereof directed over a suitable platen, of a knife adapted to be reciprocated across the path of movement of one of said strips only and engage said strip, a spring for reciprocating said knife and said file, means normally checking movement of said knife and file under action of said spring, means for automatically releasing said checking means when a predetermined length of strip has been drawn across said platen.
35. 14. In an autographic register, the combination, with means for rotatably mounting a plurality of rolls of paper strips with the end portions thereof directed over a suitable platen, and means operable to advance said strips in unison across said platen, of a knife adapted to be reciprocated across the path of movement of one of said strips only and engage said strip, normally checked means constantly tending to reciprocate said knife and said file, and means actuated by said advancing means to release said checking means when a predetermined length of strip has been drawn across said platen.
40. 15. In an autographic register, the combination, with means for rotatably mounting a plurality of rolls of paper strips with the end portions thereof directed over a suitable platen, and means operable to advance said strips in unison across said platen, of a knife adapted to be reciprocated across the path of movement of one of said strips only and engage the said strip, a spring for reciprocating said knife and said file, means normally checking movement of said knife and file under action of said spring, and means actuated by said advancing means for automatically releasing said checking means when a predetermined length of strip has been drawn across said platen.
45. 16. In an autographic register, the combination with means for rotatably mounting a plurality of rolls of paper strips with the end portions thereof directed over a suitable platen, and means operable to advance said strips in unison across said platen, of a knife adapted to be reciprocated across the path of movement of said strips, a piercing file adapted to be reciprocated across the path of movement of one of said strips only and engage the said strip, a spring for reciprocating said knife and said file, means normally checking movement of said knife and file under action of said spring, means actuated by said advancing means for automatically releasing said checking means when a predetermined length of strip has been drawn across said platen.

ated by said advancing means for automatically releasing said checking means when a predetermined length of strip has been drawn across said platen, and means for re-
5 storing energy of said spring by the operation of withdrawing said strips.

In testimony of the foregoing, I have

hereunto set my hand in the presence of two
witnesses.
